STAND FOR AN AMUSEMENT MACHINE
OR THE LIKE

John Richard Heywood, Rosebery, New South Wales, Australia, assignor to Ainsworth Consolidated Industries Pty. Ltd., Rosebery, New South Wales, Australia, a company incorporated of Australia

Filed Aug. 13, 1962, Ser. No. 71,253

Claims priority, application Australia, Mar. 27, 1962,
43,248

Term of patent 3½ years

(Cl. D52—3)

FIG. 1 is a perspective view from the front of a stand for an amusement machine or the like embodying the new design;

FIG. 2 is an enlarged perspective view taken from the rear and side opposite that shown in FIG. 1, and

FIG. 3 is an elevational view, on a reduced scale, taken from the side shown in FIG. 1.

I claim:

The ornamental design for a stand for an amusement machine or the like, as shown and described.
